UNITED STATES PATENT OFFICE.

WILHELM SCHACHENMEIER, OF MUNICH, GERMANY.

SUSPENSION BRIDGE.

Application filed November 2, 1921, Serial No. 512,220, and in Germany April 25, 1921.

My invention relates to suspension bridges and has for its object to provide a novel and efficient construction whereby wind pressure is effectively resisted and deflections of the bridge in horizontal, transverse directions is materially diminished and substantially eliminated. Difficulty has heretofore been experienced in providing a satisfactory arrangement for adequately resisting wind pressure against suspension bridges, which pressure, generally speaking, is principally in horizontal directions. In many cases a wind-bracing has been arranged below the floor of the bridge to function in the manner of a horizontal beam-girder. Cables running over all of the spans and located in the floor for effecting a horizontal rigidity and stiffness in the bridge have also been utilized but have proved insufficient for the intended purposes because of the small camber of the cable deflection. The hitherto existing arrangements are especially inefficient for long spans because the width of the floor, in such cases, in proportion to the length of span, is too small to provide a sufficient stiffness in the wind-bracing. In such cases, it has been attempted to take up and counteract the force of the wind by means of cables which project laterally beyond the floor of the bridge and are connected therewith by means of horizontal struts, thus forming a horizontal suspension-girder. With such arrangements it is impossible to extend the cables sufficiently to prevent sagging thereof by their own weight, so that the forces of the wind are resisted only when the slack of the cables has been taken up, which results in a considerable horizontal deflection of the whole superstructure. The arrangements in question are, therefore, very unsatisfactory and are used in practice only in rare instances. The present invention overcomes all of the disadvantages of existing arrangements and provides an improved construction in which wind-cables are employed in bridges in such a manner that their efficiency has been increased to a high degree. The invention will be fully described hereinafter and the features of novelty will be pointed out in the appended claims.

In the accompanying drawings, which diagrammatically illustrate examples of the invention without defining its limits, Figure 1 is an elevation of a bridge embodying the invention; Fig. 2 is a plan view thereof;

Figs. 3 and 4 are cross-sections taken respectively near a pier and near the centre of the bridge, and Fig. 5 is a diagrammatic cross-section illustrating one method whereby the wind-cables may be rendered taut.

Referring more particularly to Figs. 1 to 4 inclusive of the drawings, *a* represents the wind-cables and *b* are cross-bars or struts whereby said cables are stretched or rendered taut; in the preferred arrangement the two wind-cables *a* cross each other by about the width of the bridge at approximately the centre of the inner span of the bridge and also near the outer end of each end span, as shown in Fig. 2. The wind-cables are anchored in any convenient manner, preferably near the anchorages of the main cables *e*, which are operatively combined with the piers in the well known way. The floor *c* of the bridge is suspended from the main cables *e* by means of suspension members *d* while the wind-cables *a* are connected with each other and with the main girders of the bridge through the medium of horizontal members *f*; the wind cables *a* are suspended from the main cables *e* by means of suspension members *g* which are located in relatively close relation to each other. The wind-cables *a* are located in a plane which corresponds as nearly as possible to the central plane of the effective wind forces.

The required and adequate initial stress or pull in the wind-cables *a* whereby the latter are rendered taut for resisting the force of the wind, is produced by shifting each cross-bar *b* transversely outward relatively to the bridge. This may be done in any suitable manner as, for instance, by means of a hydraulic jack or other convenient mechanism or, as shown diagrammatically in Fig. 5, the dead-load of the superstructure may be utilized for adjusting said cross-bars *b*. In such case pylons or posts *h* and *i* support the main cables *e* and carry the whole dead-load of the superstructure; the wind-cables *a* are fixed to the ends of the cross-bars *b* which, in this instance, consist of two sections horizontally adjustable, for instance, on roller bearings *m* and *n*. Struts *k* and *l* extend between the heads of the pylons *h* and *i* at inclinations, as shown, and the cross-bars *b* are subjected to a compression force as soon as the pylons are mechanically lowered. This force is transmitted by the struts *k* and *l* to the cross-bars *b* and causes the latter to be moved out-

wardly in opposite directions whereby the cables *a* are rendered taut and placed under a stress; by predetermining the inclination or slope of the struts *k* and *l* the pull or 5 resistance against the wind forces exerted by said cables *a* may be adjusted to just the degree required in each structure. The roller bearings *m* and *n* facilitate the adjustment or shifting of the cross-bars *b* and 10 bear the vertical component of the strut pressure; these bearings, as well as the struts *k* and *l* may be removed from the structure after the wind-cables *a* have been properly put in stress. The cross-bars *b* 15 may be temporarily secured in their finally adjusted positions in any suitable manner, as by means of splicing and are permanently and rigidly connected with the whole pylon construction, for instance, by riveting or bolting.

It will be understood that instead of the struts *k* and *l* and roller bearings *m* and *n* other means, such as a system of hinged struts, may be utilized for bringing the 25 cables *a* to the desired and adequate degree of tautness.

In suspension bridges which do not include side spans and have only a middle span and approaches, the wind-cables *a* may 30 be arranged in a manner similar to that described hereinbefore. In such constructions special anchorages may be provided for anchoring said cables or those anchorages whereby the main cables are fastened may 35 be used for the purpose. The above described wind-bracing by cables may, under certain conditions, be applied also to other types of bridges, especially if the width of the bridge is extremely small in proportion 40 to the length of span. The arrangement may be incorporated in arch-bridges with particularly efficient results as in such cases the horizontal arch pressure will be partially neutralized by the horizontal pull of 45 the wind-cables upon the end abutments of the bridge.

In the improved arrangement the wind-cables run continuously over all the spans of the bridge and are anchored within the 50 same supports in which the main girder-cables are anchored, so that they project considerably beyond the floor as well as beyond the masonry piers. In this way the requisite depth of both wind-cables necessary 55 for the lateral bearing capacity of the bridge is secured, the outer ends of the iron cross-bars *b* serving as points of support for said wind-cables. The wind-cables are given an artificial initial stress to an adequate extent by forcing the cross-bars *b* apart. In this way the two cables are connected to form a statical system in which 60 both cables, instead of acting separately, one for one direction of wind and the other for another direction of wind, are forced to co-

operate in a manner similar to the two chords of a beam girder. With this arrangement, any wind load causes tension stress in one cable and compression stress in the other which is possible as far as compression means a lessening of the previous or initial tension stress acting in the whole system from the beginning. The initial pull is so high that it will also neutralize elongation of the cables due to rising temperature 75 so that even the highest temperature likely to exist coincidentally with full wind loading will not cause a slackening or loosening of said cables. The system being stable only for an equally distributed total wind load over the whole length of the bridge, it is connected with a horizontal stiffening girder, the chords of which are at the same time chord-members of the two vertical main stiffening girders. The wind-cables, 80 as well as the cross-bars, are suspended from the main cables of the bridge by means of inclined tension members whereby said wind-cables are forced to remain within the plane of the wind-bracing in all parts 85 of the bridge including those parts of the span where said cables project outside of the planes of the main girders.

Thorough investigation has proved that the arrangements herein shown and described provide very essential advantages over existing methods of wind-bracing and that these advantages increase as the span of the bridge increases. For instance, in 90 a bridge having a middle span of 3300 feet and a total length of 6600 feet, the result was a gain in steel construction of 6000 tons, which means about 7% of the total dead-load of the bridge. In addition to this, 95 the elastic deflections of the bridge in horizontal directions are diminished to a very considerable extent.

Various changes in the specific form shown and described may be made within the scope of the claims without departing 100 from the spirit of my invention.

I claim:

1. The combination of a bridge including panels and piers, horizontal overlapping cables anchored in the main abutments, rods 115 connecting said cables at every panel and extensible sectional cross-bars connecting said cables at every pier, the sections of said crossbars being forced apart and anchored to said bridge whereby said cables comprising a statical system and being under an initial tension stress which prevents sagging of said cables in consequence of wind pressure, temperature increases or 120 their own dead weight.

2. The combination of a bridge, wind bracing cables extending horizontally over said bridge, cross-bars extending transversely of the bridge and connected with said cables, and means whereby the dead load 125

of the bridge is effective upon said cross-bars to place said cables under an adequate initial stress.

3. The combination of a bridge, wind bracing cables extending horizontally over said bridge, and means for placing said cables under an adequate initial stress by the action of the dead load of said bridge.

4. In a bridge, transversely extensible struts connected with said bridge, cables extending longitudinally between the outer ends of said struts, said cables being under initial tension and lying in substantial curves in a common horizontal plane, said curves intersecting each other at two points intermediate said struts, and means for con-

necting said cables to the girders of the bridge at a plurality of points.

5. The combination with a bridge of a pair of cables extending longitudinally of said bridge in a horizontal plane, said cables having their ends anchored to the main abutments of said bridge, extensible crossbars connected with said bridge and engaging said cables intermediate the ends thereof, and said crossbars being extended under a compression stress to place said cables under an initial artificially produced, predetermined tension.

In testimony whereof I have hereunto set my hand.

WILHELM SCHACHENMEIER.
